ELECTRIC RECTIFIER CONSTRUCTION

Oskar Seitz, Baden, Switzerland, assignor to
Aktiengesellschaft Brown Boveri & Cie., Baden,
Switzerland, a joint-stock company of Switzerland

Application June 20, 1931, Serial No. 545,663

2 Claims. (Cl. 250—27.5)

This invention relates to improvements in electric power rectifiers of the metal tank enclosed metallic vapor type and particularly to a construction for retaining the cathode material 5 therein.

Electric power rectifiers of the present time are built with metal tanks which are double-walled to permit the circulation of the cooling fluid in the space within the walls. The cathode material is 10 retained within a well which is usually formed from a cylinder of insulating material abutting against the tank bottom about an aperture therethrough. The open lower end of the cylinder is closed by a plate which may also be made 15 hollow to permit the circulation of a cooling medium therethrough.

Due to the fact that an electric current rectifier of the metallic vapor type must be exhausted to a high degree of evacuation and that such 20 evacuation must be maintained while the rectifier is in operation, it is necessary that the joints between the insulation and the metal portions be gas-tight. To secure such gas-tight joints, the insulation and metal portions are pressed tightly 25 together thereby highly stressing the insulation which is usually porcelain because of its insulating and heat-resistive qualities. Such stresses, particularly when the porcelains are heated, cause chipping, cracking and even complete destruction 30 of the porcelain cylinder. To produce the necessary gas-tight joints, it is likewise necessary to provide elaborate seals, the most successful of which is a well-known mercury seal.

It is, therefore, among the objects of the present invention to provide a cathode well construction for electric power rectifiers in which the use 35 of insulation material as a portion of the tank structure is restricted to its use as gaskets between metallic portions.

Another object of the invention is to provide 40 a cathode retaining construction for electric power rectifiers which will have only a single joint in the cathode well and which joint will be unaffected by any stresses exerted thereon.

Another object of the invention is to provide 45 a cathode well construction for electric power rectifiers in which the single joint present in the cathode well construction is sealed merely by a gasket of compressible material.

Another object of the invention is to provide 50 a structure arranged and retained internally within the cathode retaining structure of an electric power rectifier for the purpose of protecting a compressible gasket arranged between the metal-

lic portions of the structure from heat and other destructive forces exerted thereon.

Objects and advantages, other than those above set forth, will be apparent from the following description when read in connection with the accompanying drawing, of which:

Fig. 1 is a vertical cross section through a cathode well embodying the present invention; and

Fig. 2 is a fragmentary vertical cross sectional view illustrating, in enlarged scale, the assembled relation of certain of the elements shown in Fig. 1.

Referring more particularly to the drawing by characters of reference, the reference numeral 1 designates a portion of the double-walled bottom of a tank forming the enclosure for the anodes, etc. of an electric power rectifier as is well-known. An aperture is formed in the tank bottom 1 and the double walls of the bottom are sealed by a ring 2 thereby closing the opening between the walls and forming a space for the circulation of a cooling medium therethrough. The ring 2 is formed with a seat to receive a resilient gasket 3 which seals the joint between the ring 2 and a cathode plate 4. The plate 4 is drawn tightly against the gasket 3 by bolts 6 passing through the plate and into the ring 2. All of the elaborate seals heretofore considered necessary are thus avoided and the use of an extensive cylinder of relatively fragile insulating material is not required. The plate 4 is preferably made double-walled as shown and is supplied with a suitable cooling medium through an inlet 7. The cooling medium is circulated by permitting the escape thereof through an outlet pipe 8.

The cathode plate 4 forming the cathode well proper retains a quantity of vaporizable conductive material 9, such as mercury, forming the cathode to which the arc attaches. A sufficient quantity of mercury is present to permit retention of some mercury within the well even at the maximum vaporization rate of the rectifier during operation. The mercury condensed on the cooled tank wall is returned to the cathode well as is usual.

To permit the use of materials injuriously affected by heat as the gasket 3, a cylinder 11 of suitable heat resistive material such as quartz is retained within the cathode plate. The ground upper edge of the cylinder 11 is resiliently retained in close contact with a seat formed in a relatively heavy plate 12 of a material not affected by the vapor rising from the cathode. The plate 12 is held in spaced relation from the

110

bottom 1 by a ring 13 fastened thereto by bolts passing through both the plate 12 and the ring 13 into the tank bottom wall 1. An arc flowing from the anodes (not shown) to the cathode is thus prevented from passing behind the cylinder 11 thereby injuring the gasket and is likewise prevented from attaching on the upwardly extending portion of the cathode plate 4 which would be damaged or destroyed thereby.

10 The cylinder 11 is pressed upwardly against the protective plate 12 by means of helical springs 16 resting in recesses formed in the cathode plate 4. The springs are provided with caps 17 to prevent uneven seating of the cylinder on the spring and to aid in guiding the expansion and compression movements of the spring.

15 A strap 18 is secured in spaced relation along a portion of the edge of the cap, and a strap 21 having a bow-shaped leaf spring 22 secured thereto at right angles to the axis of the strap 21 is passed between the top of the cap 17 and the strap 18. When the cylinder 11 is properly placed on the springs, the straps 21 are so adjusted by bending the ends thereof over the edges of the 20 caps as to produce a slight spring pressure on the cylinder from all sides thereby aiding in maintaining the cylinder in a centered position.

25 Although but one embodiment of the present invention has been illustrated and described, it will be apparent to those skilled in the art that various changes and modifications may be made therein without departing from the spirit of the invention or from the scope of the appended 30 claims.

35 The invention claimed is:

1. In an electric current rectifier, the combination of a casing of electrically conductive material having an aperture through the bottom thereof, a receptacle containing vaporizable electrode ma-

40

terial supported on said casing and closing said aperture therein, an annular plate supported within said casing concentrically with said aperture and spaced therefrom, a cylinder of insulating material supported within said aperture in contact with said plate and in contact with said electrode material, a plurality of springs arranged in spaced relation about said cylinder for causing the latter to be yieldingly pressed into contact with said plate, pressure equalizing and guiding members arranged about said springs, and members resiliently affixing said guiding members to said cylinder for supporting the latter within and concentric with the said aperture.

2. In an electric current rectifier, the combination of a casing of electrically conductive material having an aperture through the bottom thereof, a receptacle containing vaporizable electrode material supported on said casing and closing the aperture therein, said receptacle having a plurality of spaced recesses in the bottom wall thereof, an annular plate supported within said casing concentrically with said aperture and spaced therefrom, a cylinder of insulating material supported within said aperture in contact with said plate and in contact with said electrode material, a plurality of springs supported within said recesses for causing said cylinder to be yieldingly pressed into contact with said plate, pressure equalizing and guiding members arranged about said springs for supporting said cylinder, and members resiliently affixing said guiding members to said cylinder for maintaining said cylinder concentric with said aperture, the said cylinder being operable to guide arcs flowing to 100 said electrode material and to limit the flow of heat from said material to the walls of said receptacle.
